UNITED STATES PATENT OFFICE.

ARTHUR STANLEY, OF BOSTON, MASSACHUSETTS.

BILL OR INVOICE CONTAINER FOR SHIPPERS' USE.

Application filed October 18, 1922. Serial No. 595,416.

To all whom it may concern:

Be it known that I, ARTHUR STANLEY, a citizen of the United States of America, and a resident of Boston, in the county of 5 Suffolk and Commonwealth of Massachusetts, have invented certain new and useful Improvements in Bill or Invoice Containers for Shippers' Use, of which the following is a specification.

10 This invention relates to a bill or invoice container for shippers' use, and more particularly to one adapted to be attached to the exterior of a case, box, or package about to be shipped. It is an object of the invention to produce a simple, inexpensive and 15 readily applied container of this class, that affords a means of access to the bill or invoice contained therein, before the actual unpacking of the case, box, or package takes 20 place.

It is a further object of the invention to produce such a container at a low manufacturing cost, that is serviceable and less expensive to the shipper and the employer 25 than containers at present used for the same purpose.

Another object of the invention being to make the container of a single sheet of material, having but one fold to produce 30 two leaves, each of which has a portion thereof adapted to be adhesively attached to the package, and when so attached may be torn therefrom, carrying with it the bill or invoice contained therein.

35 A still further object of the invention is to so arrange the exposed face of the container that the contents thereof will be plainly inscribed thereon, as well as from whom received, a space reserved for the date 40 of shipping if desired, and a brief description of the manner or form of shipment, and space reserved for the number of the kind or form.

Heretofore in shipping merchandise it has 45 been customary to enclose a bill or invoice with the goods, sometimes putting the bill in an envelope with an inscription thereon, but more often packing it loosely with the goods.

50 In either event the bill or invoice was often times the last thing to be unpacked, or was often stowed in an obscure corner and subsequently lost or at least the finding thereof delayed, or was carelessly overlooked during the unpacking process.

Under such conditions, a rapid and ac-

curate checking up of the goods as it was removed from the case or package could not be made, but needless delay occurred, and quite often resulted in a request for a 60 duplicate invoice from the shipper.

The use of an envelope did not lessen the above troubles but did add to the expense, and in view of these facts it is an object of this invention to produce a bill 65 or invoice container adapted to be externally applied to a package containing merchandise, and which is in plain sight and ready at hand with the bill or invoice therein to begin checking up immediately upon 70 opening the package.

The invention consists in certain features which will be fully understood from a description of the drawings and the claim hereinafter given.

75 Of the drawings:—

Figure 1 represents in top plan view a package containing merchandise ready for shipment, having the invention applied thereto.

80 Figure 2 a developed view of the container.

Figure 3 a view similar to Figure 2 but showing the opposite face thereof.

85 Figure 4 a section, in diagram, taken on the line 4—4 Figure 1, showing the container with a bill or invoice therein.

Figure 5 a perspective view of a portion of a package with the container partially affixed thereto and showing a bill or invoice 90 in position to be sealed.

Like characters represent like parts throughout the several figures of the drawings.

95 Referring to the drawings:—

The drawings herewith show a simple form of the present invention, but it will be understood that slight changes might be made therein as to size, shape and material used, without departing from its spirit and scope.

In this instance of the invention, the container is composed of a single sheet of material 10 the leaf or flap 11 having the exposed face thereon, being wider and longer 105 than the under flap or leaf 12, to provide a margin like extension 13 on the sides and bottom of said flap 11.

The flap 12 will be folded along the dotted line 14 to assume a position behind 110 the flap 11 as seen in the diagram Figure 4, and is provided with gummed portions

15 and 16, see Figure 2, which are adapted to adhere to the package as indicated in Figure 5. If desired the entire face of flap 12 contacting with the package may be 5 gummed but for the purpose of easy removal from the package it is preferred to apply the gum as shown.

The gummed portion 15 does not extend the full width of the flap, there being an 10 unguammed portion 17 which does not adhere to the package and which conveniently provides a means to insert a finger, or finger nail thereunder, when it is desired to tear the container from the package. The main 15 flap 11, as before stated, has the marginal extension 13, which in this instance is gummed, as shown in Figures 3 and 5, and when the bill or invoice 18 is placed as shown in said Figure 5, the said flap 11 will be folded, 20 thereover and the gummed margin caused to adhere to the package as indicated in Figure 1.

Thus, the now rear, or bottom flap 12, is adhesively attached to the package by the 25 gum at its lower edge, as at 16, and for the greater part of its width at the upper edge as 15, while the flap 11 is likewise attached directly to the package by the gum of the margin 13 at three edges thereof.

30 This arrangement results in a serviceable bill container that is extremely cheap to produce, and practical to use, and as it occupies a prominent position on the package, it is bound to be seen and its contents removed before the merchandise in the package is unpacked, and therefore the goods 35 may be checked up as rapidly as removed.

As it is an object of the invention to

plainly designate on the container the contents thereof, though briefly, the exposed 40 face thereof may have inscribed thereon the words "Invoice" or "Bill" or other inscription according to article therein.

Provision is also made for the name of the shipper and a space 19 reserved for the date of shipping and provision made for the kind of shipment, whether a case, box, bundle or the like and adjacent each, a space reserved for numerals to designate the number of each kind. 45 50

In fact the inscription thereon, and spaces reserved, may be altered to suit the occasion, or use.

Having described the invention I claim:

A container of the class described consisting of a single sheet of material folded to form the front and rear walls thereof, said rear wall being provided with an adhesive to affix it to a package, said front wall being extended beyond said rear wall at three 60 edges thereof, said extended portion having adhesive on the inner face thereof whereby said front wall may be affixed to said package to form a sealed container; a space on the face of the front wall reserved for date of shipment package description indicia on said front wall face having space reserved adjacent thereto for other designating characters; and means consisting of an unguammed portion of said rear wall at one edge 65 70 thereof whereby said sealed container may be torn from said package.

Signed by me at Boston, Massachusetts, this 11th day of October, 1922.

ARTHUR STANLEY.
